UNITED STATES PATENT OFFICE.

JOSEPH D. MOORE, OF JACKSONVILLE, FLORIDA, ASSIGNOR OF ONE-HALF TO JAMES S. PETERSON, OF JACKSONVILLE, FLORIDA.

SWITCH LOCK.

Application filed February 28, 1923. Serial No. 621,807.

To all whom it may concern:

Be it known that I, JOSEPH D. MOORE, a citizen of the United States, and a resident of Jacksonville, in the county of Duval and State of Florida, have invented certain new and useful Improvements in Switch Locks, of which the following is a specification.

My present invention relates generally to switch locks and more particularly to switch locks of the type described and claimed in my Patent 1,098,958 dated June 2nd, 1914, with respect to which my application covers certain improvements whose object in the first instance is to permit of the release of the lock by virtue of the initial movement of the switch throwing lever, and at the same time provide such connections that the switch stand and the switch throwing parts will be so divorced from the switch that the latter will be unaffected by breakage of the switch stand and its support either in whole or in part.

A further object is the provision of certain improvements in the main switch slide plate as well as in the shape of the lock releasing lever whereby to avoid operating disadvantages to which my former construction was susceptible.

In the accompanying drawings illustrating my present invention and forming a part of this application,

Figure 1 is a perspective view illustrating the practical application of my invention,

Figure 2 is a perspective view of the switch throwing shaft as well as the lock releasing upright and portions of connections of these parts,

Figure 3 is a detail perspective view of the slide plate and the parts carried thereby,

Figure 4 is a transverse vertical section showing the practical application of my invention as in Figure 1,

Figure 5 is a vertical sectional view through the switch stand, and

Figure 6 is a detail perspective view of certain parts of the switch stand and switch throwing mechanism.

Referring now to these figures I have shown in Figure 1 spaced rails 10 and 11 and movable switch points 12 and 13, the latter of which are connected by tie bars 14 and are shiftable at their extremities upon slide plates 15 and 16, the latter known as a "No. 1" slide plate. These slide plates are securely fastened upon one of a pair of ties

17 extended at one end materially beyond the ends of the other ties so that these extended portions form the supports for the base 18 of the switch stand 19 in the latter of which an upright shaft 20 is rotatable, 60 having at its upper end as usual a semaphore 21 and having at its lower end a crank 22 joined by a connecting rod 23 with one extended end of one of the tie bars 14.

As in my previous patent the main slide 65 plate 16 has a downwardly offset shelf 24 at one side, which depends between the ties 17 and to which is secured one end of an upwardly and outwardly inclined leaf spring 25 having beneath its outer upper end a coil 70 spring 26, this free end of the spring 25 being thus supplemented by the spring 26 bearing upwardly beneath the free outer end of the lock plate 27. This lock plate whose outer shouldered portion 28 is adapted for 75 engagement with the outer edge of the base of rail 11, is connected in vertically movable or swingable relation at its inner end to the extremity of the switch point 13 by virtue of vertical spring bolts 29 so that when the 80 switch point 13 is shifted outwardly against the inner surface of rail 11, the lock plate will be pressed vertically into locking position and securely hold the switch point against the rail until the outer shouldered portion 28 of the lock plate is pressed downwardly to released position where it may slide beneath the rail 11 and switch point 13 is shifted inwardly away from the rail 11.

In accordance with my present improvements the free side edge and one end of the downwardly offset shelf 24 of the slide plate 16 are provided with upstanding walls 30 and 31, the former being cut away upon an incline corresponding to the incline of the leaf spring 25 and the latter upstanding at the free end of the leaf spring so that this leaf spring is thus boxed to the extent of preventing dirt and débris from getting beneath the leaf spring and obstructing its free yielding movement in a downward direction. In further accordance with my present invention the slide plate 16 has at its outer end an extended tongue 32 from which a stud 33 projects laterally to form the fulcrum of the lock releasing lever 34, the latter being in the nature of a bell crank whose inwardly projecting arm is adapted to bear upon the free end of the lock plate 27 when the parts are in the locked position and 100

105

110

whose outer depending arm receives one end of a connecting rod 35. This connecting rod is preferably in two sections connected by a turnbuckle 36 and extending through a guide 37, its opposite end being connected to one end of a rocker arm 38 from which, intermediate its ends, a foot plate 39 projects beneath a portion of the switch stand 19 as plainly seen by reference to Figures 2 and 4.

The free end of the lock releasing bell crank 34 adapted as before stated to rest upon the shouldered outer portion 28 of the lock plate 27 so that when the depending arm of the bell crank is shifted outwardly the said lock plate will be depressed to locked position, is preferably provided at its free end with a reduced rail engaging nose 40 adapted to engage the base of the rail 11 when the lock plate is depressed just sufficient to move the same to released position, in order to prevent rocking movement of the bell crank lever to such an extent that its inwardly projecting arm might project into the path of outward movement of the lock plate 27 when the latter is subsequently shifted outwardly toward the locked position.

Referring now to Figures 2, 4 and 5 particularly it will be noted that the switch actuating lever 41 is fulcrumed intermediate its ends as at 42 to the upper squared portion of the upright shaft 20 and is pivotally connected at 43 between its handle and its fulcrum 42, to the upper ends of arms 44 upstanding from the vertically shiftable cap plate 45 of the switch stand 19, which arms are pivotally connected at their lower ends to the cap plate. Beyond its fulcrum 42 the lever 41 is provided with a presser plate 46 above the upper end of a vertically shiftable presser rod 47 upstanding through the switch stand 19 with its lower end disposed above and movable downwardly into engagement with the foot piece 39 of the rocker arm 38.

The upper portion of the presser rod 47 projects vertically through an arcuate slot 48 of the cap plate 45, the latter of which in its normal lowered position rests upon the upper surface of the switch stand 19 and is prevented from rotation and in turn holds the shaft 20 against rotation by virtue of an upstanding squared and reduced boss 49 of the switch stand and a squared socket 50 in the lower surface of the cap plate into which the boss extends when the cap plate is lowered onto the switch stand. While I have shown no particular form of locking means, it will be understood that in accordance with the usual practice the switch throwing lever 41 will be locked in its lowered position to the switch stand 19 by any of the well known locking means for this purpose and that when thus locked in its

lowered position the switch point 13 is against the rail 11 and locked in contact therewith by the locking plate 27, the presser rod 47 being at this time in its upper position as shown in Figure 4 above the foot piece 39 of the rocker arm 38 so that should the switch stand, with the parts in this position, be partly or wholly demolished the locking plate 27 will remain in locked position holding the switch point 13 against the rail 11. Furthermore in this, the locked position of the parts, the presser rod 47 is positively held from lowering movement by virtue of a locking bar 51 pivotally connected at one end as at 52 to one side of the switch throwing lever 41 and extending through the guide bracket 53 upstanding from the cap plate 45, the presser rod 47 having an annular groove 54 into which the free end of the locking bar 51 extends when the switch throwing lever 41 is in its lowered position.

When it is desired to throw the switch, that is shift the switch points 12 and 13 so that the former will engage rail 10 and the latter will move away from rail 11, the switch throwing lever 41 must first be raised in order to lift the cap plate 45 free of the switch stand boss 49 and during this movement the locking bar 51 is withdrawn from engagement with the presser rod 47 and the presser plate 46 of lever 41 moves downwardly into engagement with the upper end of the presser rod 47 so that the latter will be lowered and upon engagement at its lower end with the foot piece 39 will rock the rocker arm 38 and in this way shift the connecting rod 35 in the direction of its length so as to force the inwardly projecting horizontal arm 34 of the bell crank 34 downwardly into engagement with the shouldered end 28 of the lock plate 27 and in turn lower said lock plate to released position.

This action of the parts takes place during the upward swinging movement of the switch lever 41 and is complete when said lever is elevated to the position shown in Figures 5 and 6 wherein the cap plate 45 is above the boss 49 of the switch stand and the shaft 20 is thus free for rotatable movement by swinging the switch throwing lever 41. This swinging movement of the lever through approximately ninety degrees is sufficient through the shaft 20 and its lower crank arm 22, to throw the switch points against rail 10 and away from rail 11 by virtue of the connecting rod 23 and its engagement with the extended portion of the tie bar 14.

When the parts are restored to the locked position shown in Figure 4 and the lever 41 is lowered, vertical movement of the lock plate 27 to locked position under tension of the springs 25 and 26 restores the presser

rod 47 to its upper position where as above stated it is securely held against accidental lowering movement by virtue of the locking bar 51 and the annular groove 54.

5 I claim:

1. In a switch lock of the character described, a vertically swingable lock plate, a slide plate for a switch point having a downwardly offset shelf at one side beneath the clock plate, a flat spring inclined along said plate and secured at one end thereto, having its other end bearing upwardly against the lock plate, said shelf having an upstanding side wall along the outer side 10 of said spring member and having an upstanding end wall across the free end of the spring for the purpose described.

2. In a switch lock, a vertically swingable lock plate, a slide plate for a switch point having a downwardly offset shelf, spring means on the said shelf bearing upwardly against the said lock plate, said shelf having walls along one side and one end to prevent the accumulation of dirt beneath the 20 said spring means, a lock releasing lever having one end bearing on the lock plate, and an extension formed on the said slide plate, having a bearing member for the said releasing lever.

3. In a switch lock, the combination with a rail and a switch point shiftable into and out of engagement with the rail, of a vertically swingable lock plate carried by the switch point and having a shouldered rail 30 engaging end, spring means for shifting said plate upwardly into engagement with the rail, and means for depressing said lock plate to released position including a lever one end of which is shiftable downwardly

35 upon the shouldered end of the lock plate, said lever having an extended lip at its said

free end engageable in its lower active position with the base of said rail to prevent downward movement of the lever into the path of return movement of the lock plate. 45

4. The combination with a switch stand and switch throwing connections including a main lever on the stand, of a switch lock, and releasing connections for the lock including elements, certain of which elements are independent of the switch stand and normally extend adjacent to and free of connection therewith and certain of which elements are supported by the stand and movable upon actuation of said lever into 50 effective engagement with the first named element.

5. In a switch lock, the combination with a switch stand and a switch throwing lever, of a presser rod upstanding through said stand, means carried by the lever for depressing said rod when the lever is raised, an automatically engageable lock plate, and lock releasing connections including a member 55 normally positioned below and free of connection with said rod and with which the lower end of the rod is engageable.

6. In a switch lock, the combination with a switch stand and a switch throwing lever, of a presser rod upstanding through said stand, means carried by the lever for depressing said rod when the lever is raised, an automatically engageable lock plate, lock releasing connections including a member 70 with which the lower end of the rod is engageable, and means carried by said switch throwing lever and said presser rod and engageable when the lever is in its normal lowered position, adapted to lock the rod against vertical movement. 75

JOSEPH D. MOORE.
